US00D851671S

(12) **United States Design Patent** (10) **Patent No.:** **US D851,671 S**
(45) **Date of Patent:** **** Jun. 18, 2019**

(54) **DISPLAY SCREEN OR PORTION THEREOF WITH GRAPHICAL USER INTERFACE**

(71) Applicant: **WhatsApp Inc.**, Menlo Park, CA (US)

(72) Inventors: **Charles Donald Deets, Jr.**, Palo Alto, CA (US); **Randall Sarafa**, San Francisco, CA (US); **Anton Borzov**, Palo Alto, CA (US); **Zafir Khan**, Redwood City, CA (US)

(73) Assignee: **WHATSAPP INC.**, Menlo Park, CA (US)

(**) Term: **15 Years**

(21) Appl. No.: **29/625,978**

(22) Filed: **Nov. 14, 2017**

(57) **CLAIM**

The ornamental design for a display screen or portion thereof with graphical user interface, as shown and described.

DESCRIPTION

The FIGURE is a front view of a display screen or portion thereof with graphical user interface showing the new design.

The outer broken lines show a display screen or portion thereof and form no part of the claimed design. The remaining broken lines show elements of the graphical user interface that form no part of the claimed design.

1 Claim, 1 Drawing Sheet
